UNITED STATES PATENT OFFICE.

MORRIS SHEINMAN, OF NEW YORK, N. Y.

BURGLAR-PROOF SPRING-LOCK.

1,253,734.

Specification of Letters Patent.

Patented Jan. 15, 1918.

Application filed December 19, 1916. Serial No. 137,793.

To all whom it may concern:

Be it known that I, MORRIS SHEINMAN, a citizen of the United States, and a resident of New York, borough of Bronx, county of New York, and State of New York, have invented certain new and useful Improvements in Burglar-Proof Spring-Locks, of which the following is a full, clear, and exact description.

10 This invention relates to locks for doors, and has for its principal object the provision of a simple and substantially burglar-proof lock adapted for use in connection with either swinging or sliding doors.

15 A further object of the invention is to provide a lock having a bolt casing and a keeper so constructed and arranged as to prevent operation of the lock bolt by an instrument inserted between the door and door jamb.

20 A further object is to provide a lock having a vertically movable bolt provided with vertically disposed keeper-engaging lugs adapted to automatically lock when the door is closed.

25 Another important object of the invention is the provision of simple means for locking the bolt against movement by the key or knob when in either its lower locked position or its raised unlocked position.

30 A further important object of the invention is to provide a lock having a vertically movable bolt adapted to be actuated by the key or by the knob on the inner side of the door by turning the knob or key in either direction.

35 In the drawings, Figure 1 is a horizontal sectional view showing the lock applied to a door.

Fig. 2 is a rear elevation, partly in section.

40 Fig. 3 is a front elevation, partly in section.

Fig. 4 is a vertical transverse sectional view on the line IV—IV of Fig. 2.

45 Fig. 5 is a vertical transverse sectional view on the line V—V of Fig. 2; and

Fig. 6 is a vertical transverse section on the line VI—VI of Fig. 2.

Referring to the various parts by numerals, 1 designates the keeper, preferably 50 formed of angle iron, countersunk in the door jamb 2 and secured thereto by screws or other suitable fastening means. The keeper is provided with a pair of outwardly projecting ears 14 having vertically extending apertures 15 therethrough. The body portion of the bolt casing is preferably

formed of an integral and substantially rectangular box-like casting 3. A portion of the inner wall of the casing is formed integrally with the top and bottom wall and 60 the integral end wall 3^a of the body portion 3, as shown at 4 in Figs. 1, 3 and 6, and the edge of this wall 4 is provided with an outwardly extending flange 5 adapted to seat in a recess in the edge of the door 6. A detachable plate 7 closes the opening in the inner face of the casing 3. One edge of the plate 7 is beveled and engages under the edge of the integral inner wall 4 of the casing 3, and the plate is attached to the casing 70 by a screw threaded into a lug 8 projecting from the inner face of the outer wall of the casing 3.

A vertically movable lock bolt 9 is slidably confined in the casing 3, said bolt being 75 guided by lugs 10 projecting from the outer wall of the casing and extending through slots 11 in the bolt. At its outer end the bolt is provided with a pair of outwardly extending arms 12 having depending 80 keeper-engaging latch lugs 13. The lugs 13 are beveled as shown at 16 so that when the door is closed the lugs will ride up over the beveled outer ends of the keeper ears 14 and drop into the apertures 15 in the ears. 85 The walls 3 and 4 of the casing are provided with apertures to permit the ears 14 of the keeper to project through both sides of the casing when the door is closed, the inner edge of the aperture in the inner wall 4 being spaced a distance from the flange 5, so that a solid portion of said wall 4 will cover the intervening space between the adjacent edges of the door and jamb, as clearly shown at 4 in Fig. 1 of the drawing. In other 95 words, the apertures in the bolt casing are formed to entirely lie beyond the edge of the jamb, thereby making it impossible to insert a tool between the door and jamb and engage the bolt or the interior of the lock. 100 The solid integral end wall 3^a contacts with the keeper ears 14 and prevents the breaking or bending of the latch lugs 13 by lateral pressure should a tool be applied between the door and jamb and prying pressure exerted.

The bolt 9 is normally held in its lower or locked position, as shown in full lines in Figs. 2 and 3, by means of a compression spring 17 interposed between the upper edge 110 of the bolt and a lug 18 projecting from the wall 3 of the casing. A stem 19 extends up-

wardly from the bolt and passes freely through the spring 17 and an aperture in the lug 18. A suitable washer is preferably interposed between the end of the spring and the under side of lug 18.

At the end thereof opposite the locking lugs, the bolt 9 is provided with an extension 20, which projects beyond the axes of the bolt operating means and is slotted at 21. A portion of the front face of the extension 20 is cut away to form a web 22 and a projecting portion 23. The under edge of the projecting portion 23 is recessed to fit over the hub 24 of the two-armed bolt-lifting lever 25 keyed on the spindle of the door knob 26. The outer end of the hollow spindle is preferably headed against the face of the hub 24 of lever 25, as shown in Fig. 4, to permanently attach the lever to the spindle. It will be obvious that upon turning the knob 26 in either direction one arm of the lever 25 will engage one of the shoulders or projections 27 formed by the lower edge of the projecting portion 23 on one side of the extension 20 of the bolt and lift the bolt 9 against the action of spring 17.

A sleeve 28 is rotatably mounted in an aperture in the detachable plate 7 of the lock casing. The outer end of the sleeve 28 is closed by an integral cover plate 29 the edges of which extend beyond the outer walls of the sleeve to form retaining flanges for the sleeve. The hub 30 of a bolt-lifting arm 31 is keyed on the inner end of the sleeve 28 so as to turn therewith, and the inner end of the sleeve is headed against the hub 30 to lock the hub on the sleeve. The bolt-lifting arm 31 is operated by a key from the outside of the door. I prefer 40 to employ a lock 33 of the cylinder type. The key barrel 32 is rotatably held in the casing of the lock 33 and is provided with a flat or angular rearward extension or connecting bar 34 having a telescopic engagement with the sleeve 28 through a correspondingly shaped slot in the cap 29. The casing of the lock 33 is slidably mounted on a pair of rods 35 projecting from and rigidly connected with the detachable plate 7 50 of the casing 3. The casing of the lock 33 is recessed to form grooves 36 and shoulders 37. The outer ends of the rods 35 pass through apertures in the shoulders 37 and into the grooves or recesses 36. The rods 55 are preferably provided with longitudinal grooves adapted to receive the ends of clamping screws. By shifting the casing of the lock 33 along the rods said casing may be adjusted to bring its outer end flush 60 with the outer face of the door 6 and may be locked in its adjusted position by the screws 38. The lock 33 is adjusted upon the rods and secured in adjusted position before the assembled parts are applied and secured 65 to the door, the adjustment being made in

accordance with the known thickness of the door. The grooves terminate short of the outer ends of the rods and suitable coil springs 39 may be mounted on the rods to normally hold the lock casing at the limit 70 of its outward movement. It will be obvious that by inserting the proper key in the lock 33 and turning the key barrel 32 in either direction, the arm 31 will engage the under side of a projection 40 on the opposite side 75 of the extension 20 of the bolt 9 upon which is formed the projections or shoulders 27 and lift the bolt to unlock the door.

By terminating the longitudinal grooves short of the outer ends of the rods 35, the 80 ends of said grooves form stops or shoulders, which will be engaged by the lower ends of the clamping screws 38 should an attempt be made to remove the lock-casing from the key side of the door. In other words, there 85 is provided a lock-casing adjustably secured to the bolt-casing so that it can be inserted from the bolt-casing side of the door and cannot be removed from the key side of the door.

A latch 41, pivoted intermediate its ends on an extension 42 of the upper guide lug 10, is mounted in the casing 3, and the upper end or finger-piece thereof projects through a slot in the top wall of the casing 3. The 95 lower hooked end of the latch 41 is adapted to be swung beneath the adjacent end of the projection 40, when the bolt 9 is raised, to lock the bolt in raised position to prevent automatic locking of the door when the door 100 is closed. The lower end of the latch 41 is also adapted to be swung above the adjacent end of the projection 40 when the door is locked, to prevent unlocking of the door from the outside, thus serving as a night 105 latch. A suitable washer and a coil spring 43 are mounted on the finger-piece of the latch 41 and frictionally engage the top wall of the casing 3 to hold the latch in its adjusted positions.

An important feature of the invention is the provision of a vertically movable bolt having vertically disposed keeper-engaging lugs or latch members, the bolt being normally yieldably held in its lowermost position and the latching lugs being adapted to ride up over the keeper ears and drop into the apertures therein, thereby automatically locking the door when the same is closed.

A further important feature is the provision of simple means for preventing automatic locking of the door, when desired, and for preventing unlocking of the door from the outside by means of a key.

It will be seen also that by the construction and arrangement of the bolt casing and keeper shown and described, the adjacent edges of the door and jamb are faced with metal and the space between said edges at the inner side of the door jamb is covered 125 130

by the metal wall of the bolt casing, the bolt at this point being entirely inclosed by the four integrally cast walls of the casing. By this arrangement access to the bolt by means 5 of an instrument inserted between the edges of the door and jamb is effectually prevented. The integral end wall of the casing adjacent the keeper prevents breaking the lock by lateral pressure on the keeper ears.

10 By mounting the key barrel and the adjustable lock casing on the detachable face plate of the bolt casing, a convenient arrangement is provided whereby the complete lock may be handled and shipped without 15 danger of loss of parts. This arrangement also allows of the lock-casing being inserted from the bolt-casing side of the door. The particular construction of the sliding connections between the lock casing and the face 20 plate and between the key barrel and its associated bolt lifter, permit adjustment of the lock casing to bring its outer face flush with the outer face of doors of various thicknesses and securely fastens the lock-casing 25 to the face-plate to prevent its removal from the key side of the door, without destroying the operative connection between the key barrel and bolt-lifter.

It will be further observed that by extending 30 the end of the bolt beyond the axes of the bolt-operating mechanisms I provide for forming on opposite sides thereof the double bolt-lifting shoulders which are each engaged separately by the lifting levers on the 35 key and knob mechanisms and allow of the lifting of the bolt by turning either one of the lifting mechanisms in either direction. This particular construction further provides a short leverage between the bolt shoulders and the lifting levers and consequently 40 requires a minimum exertion to operate the bolts.

Having thus described my invention, I claim as new and desire to secure by Letters 45 Patent:—

1. A lock, comprising a keeper having projecting ears provided with vertical apertures, a bolt-casing provided with apertures adapted to receive the ears of said keeper, a vertically-slidable bolt mounted in said casing and provided with lugs adapted to engage the apertures in the keeper ears, a knob and key mechanism carried by said bolt-casing each embodying bolt-lifting levers, said bolt 50 being extended beyond the axes of said knob and key mechanism and provided with shoulders on each side of said axes adapted to be engaged by said lifting levers to lift the bolt when operated in either direction.

60 2. A lock, comprising a keeper having projecting ears provided with vertical apertures, a bolt-casing provided with apertures adapted to receive the ears of said keeper, a vertically-slidable bolt mounted in said casing and provided with lugs adapted to en-

gage the keeper ears and having a rearward extension formed with double shoulders on opposite sides thereof, and knob and key mechanisms carried by said bolt-casing with their axes positioned intermediate said 70 double shoulders and embodying lifting levers positioned to engage said shoulders to lift said bolt when either said knob or key mechanism is operated in either direction.

3. A lock, comprising a keeper, a bolt-casing having a detachable plate on its inner face, a sliding bolt in said casing, a knob and key mechanism for operating said bolt, said key mechanism embodying a pair of rods fixed to said detachable plate and 75 each being provided with a longitudinal groove terminating short of the outer end of the rod to form a shoulder, a cylinder lock adjustably mounted on said rods, and clamping screws carried by the casing of 80 said cylinder lock and adapted to engage in said grooves to fix the cylinder lock in adjusted positions and prevent its removal from the key side of the door.

4. A lock, comprising a keeper, a bolt-casing having a detachable plate on its inner face, a sliding bolt in said casing, a knob and key mechanism for operating said bolt, said key mechanism embodying a pair of rods fixed to said detachable plate and 90 each being provided with a longitudinal groove terminating short of the outer end of the rods to form a shoulder, a cylinder lock having recessed sides to form rod-engaging shoulders and adjustably mounted 95 on said rods, and clamping screws carried by the casing of said cylinder lock and adapted to engage in said grooves to fix the cylinder lock in adjusted positions and prevent its removal from the key side of the 100 door.

5. The combination with a door and door jamb, of locking devices comprising a keeper having horizontally-projecting ears provided with vertically-extending apertures, a bolt casing having an outer wall and a portion of its inner wall formed integral with one of its end walls, aligned apertures formed through said outer wall and said portion of the inner wall and inside of 110 said end wall, said apertures adapted to receive the ears of said keeper, a vertically-slidable bolt mounted in said casing and provided with depending latch lugs adapted to enter the apertures in the keeper ears, said end wall of the casing being continuous and spaced from said depending latch lugs of the bolt and forming one closed side of 115 said casing apertures, whereby said inner wall will engage the outside of said keeper 120 ears and prevent a lateral movement of the lock casing and consequently straining of the bolt and its latch lugs should a prying operation be attempted.

6. The combination with a door and door 125

5 jamb, of locking devices comprising a keeper having horizontally-projecting ears provided with vertically-extending apertures, a bolt casing having an outer wall and a portion of its inner wall formed integral with one of its end walls, aligned apertures formed through said outer wall and said portion of the inner wall and inside of said end wall, said apertures adapted to receive the ears of said keeper, said inner wall portion being provided with an outwardly-extending flange to seat in a recess in the edge of the door and a solid portion between said flange and adjacent aperture 10 adapted to cover the intervening space between the door and jamb, a vertically-slidable bolt mounted in said casing and provided with depending latch lugs adapted to enter the apertures in the keeper ears, said 15 end wall of the casing being continuous and spaced from said depending latch lugs of the bolt and forming one closed side of said casing apertures, whereby said inner wall will engage the outside of said keeper ears 20 and prevent a lateral movement of the lock casing and consequently straining of the bolt and its latch lugs should a prying operation be attempted.

7. A lock comprising a keeper having
30 projecting ears provided with vertically ex-
tending apertures, a bolt casing provided
with apertures adapted to receive the ears
of said keeper, a vertically slideable bolt
mounted in said casing and provided with
35 depending beveled lugs adapted to ride over
the keeper ears and drop into the vertically
extending apertures therein, said bolt having
a rearward extension formed with dou-
ble shoulders on opposite sides thereof, a
40 spring normally forcing said bolt down-

wardly, and knob and key mechanisms carried by said bolt casing with their axes positioned intermediate said double shoulders and embodying lifting levers positioned to engage said shoulders to lift said bolt against the tension of said spring when either said knob or key mechanism is operated in either direction. 45

8. A lock comprising a keeper having projecting ears provided with vertically extending apertures, a bolt casing provided with apertures adapted to receive the ears of said keeper, a vertically slideable bolt mounted in said casing and provided with depending beveled lugs adapted to ride over the keeper ears and drop into the vertically extending apertures therein, said bolt having a rearward extension formed with double shoulders on opposite sides thereof, a spring normally forcing said bolt downwardly, knob and key mechanisms carried by said bolt casing with their axes positioned intermediate said double shoulders and embodying lifting levers positioned to engage said shoulders to lift said bolt against the tension of said spring when either said knob or key mechanism is operated in either direction, and a pivoted manually-operable night-latch having one end adapted to alternately engage the opposite sides of one of the shoulders on the bolt to hold the bolt in a raised position against the tension of said spring to prevent automatic latching when engaged with one side of said shoulder, and lock the bolt down to prevent its operation by the key or knob when engaged with the other side of said shoulder.

This specification signed this 16th day of December A. D. 1916.

MORRIS SHEINMAN.
